UNITED STATES PATENT OFFICE.

HENRY M. BECKER, OF HARTFORD, CONNECTICUT.

DESIGN FOR A GAME.

58,012.

Specification for Design.

Patented May 31, 1921.

Application filed February 1, 1921. Serial No. 441,677. Term of patent 14 years.

To all whom it may concern:

Be it known that I, HENRY M. BECKER, a citizen of the United States, residing at Hartford, in the county of Hartford and State of Connecticut, have invented a new, original, and ornamental Design for a Game, of which the following is a specification, reference being had to the accompanying drawing, forming a part thereof.

The figure is a plan view of a game, showing my new design.

What I claim is:

The ornamental design for a game, as shown.

HENRY M. BECKER.
